UNITED STATES PATENT OFFICE.

HENRY S. YOUNG, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

Application filed September 9, 1924. Serial No. 736,698.

To all whom it may concern:

Be it known that I, HENRY S. YOUNG, a citizen of the United States, residing at Wilkinsburg, in the county of Allegheny and State of Pennsylvania, have invented certain new and useful Improvements in Railway Signaling, of which the following is a specification.

My invention relates to railway signaling, 10 and particularly to signaling for stretches of single track over which traffic moves in both directions.

I will describe two forms of signaling apparatus embodying my invention, and will 15 then point out the novel features thereof in claims.

In the accompanying drawings, Fig. 1 is a diagrammatic view showing one form of 20 signaling apparatus embodying my invention, and Fig. 2 is a view similar to Fig. 1 but showing a modification of portions of the apparatus and also embodying my invention.

Similar reference characters refer to similar parts in each of the views.

Referring first to Fig. 1, the reference characters 1 and 1' designate the track rails of a stretch of single track between two passing sidings X^A and X^D. The stretch of 30 single track is divided by insulated joints 2 into a middle or main track section B—C, a short preliminary track section A—B at one end of the main section, and a short preliminary section C—D at the other end of 35 the main section. At the points A and D only one track rail is divided by the insulated joints, whereas at the points B and C both rails are divided by such joints. Inasmuch as the railway track shown in the 40 drawing is designed for an electric railway, bonds 3 are provided to conduct the propulsion current around the rail joints at points B and C.

The main track section B—C is provided 45 with a track circuit comprising a transformer D^B and a track relay T^B. The preliminary section A—B is provided with a similar track circuit comprising a transformer D^A and a track relay T^A, and the 50 other preliminary section C—D is provided with a track circuit comprising a transformer D^C and a track relay T^C. The secondary of each transformer D is connected across the track rails through a current-limiting impedance, and the primary of each of

these transformers is connected with a source of alternating signaling current which is not shown in the drawing.

Located at the left-hand end of the stretch of track A—D is a line relay L^B, 60 and an auxiliary relay E^B. Located at the right-hand end of the stretch is a line relay L^C and an auxiliary relay E^C. The auxiliary relay E^B is preferably so designed as to have the characteristic of not closing its 65 front contacts for a considerable interval of time after the relay becomes energized; in other words, this is preferably a slow pick-up relay. The other auxiliary relay E^C, however, is of the usual type, and therefore 70 closes its front contacts immediately after the relay becomes energized.

Line relay L^B is provided with a pick-up circuit which passes from terminal F of a suitable source of current through contact 4 75 of track relay T^C, wire 5, back contact 6 of relay E^C, wire 7, contact 8 of track relay T^B, wires 9 and 10, contact 11 of track relay T^A, wires 12 and 13, winding of relay L^B, and wire 14 to terminal K of the same source of 80 current. This relay is also provided with a stick circuit which is the same as the pick-up circuit up to and including wire 9, and from wire 9 it passes through wire 15, contact 16 of relay L^B, wires 17 and 18, winding 85 of relay L^B, and wire 14 to terminal K of the source of current.

Line relay L^C is provided with pick-up and stick circuits which are similar to those for relay L^B, that is, the pick-up circuit for 90 relay L^C is controlled by contact 18 of track relay T^A, contact 20 of the track relay T^B, back contact 22 of relay E^B, and contact 25 of track relay T^C. The stick circuit for relay L^C is controlled by track relay contacts 95 18 and 20, and, of course, by contact 30 of the relay L^C itself.

The relay E^B is provided with a pick-up circuit which passes from terminal F of a suitable source of current, through front 100 point of contact 32 of relay L^B, wire 33, back contact 34 of track relay T^A, wires 35 and 36, winding of relay E^B, and wire 37 to the terminal K of the same source of current. This relay is further provided with a stick circuit which passes from terminal F, through back contact 32 of relay L^B, wire 38, front contact 39 of relay E^B, wires 40 and 36, winding of relay E^B, and wire 37 to terminal K. 105 110

The auxiliary relay E^c is provided with circuits which are similar to those for relay E^b , that is to say, the pick-up circuit for relay E^c includes the front point of contact 41 of relay L^c and back contact 43 of relay T^c , whereas the stick circuit for relay E^c includes the back point of contact 41 of relay L^c , and contact 48 of relay E^c .

Located at the left-hand end of the stretch is a signal S^b which governs traffic from left to right, and located at the right-hand end of this stretch is a signal S^c which governs traffic from right to left. Each of these signals, in the form here shown, is a light signal comprising three lamps G, Y and R, arranged when lighted to indicate "proceed", "caution" and "stop", respectively. The caution indication given by lamp Y means that the stretch of track is occupied by a train moving in the direction in which the signal governs traffic and that a following train is permitted to enter the stretch under full control. An auxiliary signal H^b is located a short distance to the right of point B, and a similar auxiliary signal H^c is located a short distance to the left of point C. Each of these signals H is likewise of the light type. When a train moving toward the right enters the stretch of track shown in the drawing and approaches signal H^b , the train must come to a stop and back out of the stretch unless this signal is lighted. Similarly, when a train moving toward the left enters the stretch and approaches signal H^c , the train must stop and back out of the stretch unless this signal is lighted.

Signal S^b is provided with a proceed indication circuit which passes from terminal F of a suitable source of current through the front point of contact 50 of relay L^b , wire 51, front point of contact 52 of relay T^b , wire 53, lamp G, and wire 54 to terminal K of the same source of current. This signal is provided with a caution circuit which passes from terminal F, through front point of contact 50 of relay L^b , wire 51, back point of contact 52 of track relay T^b , wires 55 and 56, front point of contact 57 of relay E^b , wire 58, caution lamp Y, and wire 54 to terminal K. This caution circuit will be closed when relay L^b is closed, relay T^b is open, and relay E^b is closed. Signal S^b is provided with another caution circuit which passes from terminal F, through back point of contact 50, wires 60 and 56, front point of contact 57, wire 58, caution lamp Y, and wire 54 to terminal K. This caution indication circuit will be closed when relay L^b is open and relay E^b is closed. Signal S^b is provided with a stop indication circuit which passes from terminal F, through the front point of contact 50 of relay L^b , wire 51, back point of contact 52 of track relay T^b , wires 55 and 56, back point of contact

57 of relay E^b , wire 59, stop lamp R, and wire 54 to terminal K. This circuit will be closed when track relay T^b is open, auxiliary relay E^b is open, and line relay L^b is closed. Signal S^b is provided with another stop indication circuit which passes from terminal F, through the back point of contact 50, wires 60 and 56, back point of contact 57, wire 59, lamp R, and wire 54 to terminal K. This circuit will be closed when relays L^b and E^b are both opened.

Signal S^c is provided with circuits which are similar to those just explained for signal S^b , and which will, therefore, be obvious from the drawing without detailed description.

The operation of the apparatus shown in Fig. 1, is as follows:

Assuming that a train moving toward the right enters the stretch of track shown in the drawing, when such train passes point A it will open track relay T^a , thereby opening at contact 18 the circuits for line relay L^a . The opening of line relay L^a will close at the back point of contact 65 the stop indication circuit for signal S^c , and so the stop lamp R of this signal will become lighted. The opening of track relay T^a opens at contact 11 the pick-up circuit for relay L^a , but this relay does not open because its stick circuit is closed at contact 16. The opening of track relay T^a closes at contact 34 the pick-up circuit for relay E^a , but owing to the slow pick-up characteristic of this relay it does not close its front contacts for a considerable interval of time. The opening of track relay T^a opens at the front point of contact 52 the proceed indication circuit for signal S^a and closes at the back point of contact 52 a stop indication circuit for this signal, so that lamp R becomes lighted. As soon as the front contacts of auxiliary relay E^a become closed, the stop indication circuit for signal S^a is opened at the back point of contact 57 of this relay and a caution indication circuit is closed at the front point of contact 57, so that lamp Y becomes lighted. As the train enters the main section B-C, it opens track relay T^b , and the opening of front contact 20 of this relay keeps the circuit for line relay L^b open as long as the train is any part of the main section. The opening of contact 8 of track relay T^b opens the stick circuit for line relay L^b so that this relay then opens. Relay L^b closes the stick circuit for the auxiliary relay E^b at the back point of contact 32, so that relay E^b remains closed. Signal S^b continues to give a caution indication, however, because a circuit for lamp Y is now closed through the front point of contact 57 of relay E^b and the back point of contact 50 of relay L^b . As soon as relay E^b closes its front contacts, the auxiliary signal H^b becomes lighted through

a circuit which passes from terminal F, through contact 61 of relay E^B, wire 62, and the lamp of signal H^B to terminal K. If signal H^B is lighted as the train approaches this signal, the train is authorized to proceed through the stretch of track. As the train enters section C—D, it causes track relay T^C to open, thereby keeping relay L^C open at contact 25, and keeping relay L^B open at contact 4. Relay E^C does not close because its pick-up circuit is open at the front point of contact 41 of relay L^C. Consequently, there is no change in the signal indications until the rear end of the train passes point D. When this occurs track relay T^C closes, thereby closing at contact 4 the pick-up circuit for line relay L^B. The closing of relay L^B opens at contact 32 the stick circuit for relay E^B, so that this relay now opens. Relays L^B and T^A both being closed, the circuit for proceed lamp G of signal S^B becomes energized. The closing of contact 25 of track relay T^C completes the pick-up circuit for relay L^C, so that this relay becomes closed, and since track relay T^C is already closed, the proceed indication for signal S^C becomes energized.

While a train moving toward the right occupies the main section B—C or the right-hand preliminary section C—D, a following train moving toward the right will receive a caution indication at signal S^B. Such following train may then enter the stretch but will cause no change in the signal indications because it will not affect the auxiliary relay E^B, and the caution indication circuit of signal S^B is complete through contact 57 of relay E^B and contact 50 of relay L^B. It follows that any number of trains moving in the same direction may proceed through the stretch of track at the same time, and that each train after the first will receive a caution indication at signal S^B and a proceed indication at signal H^B.

The operation of the apparatus during the passage of a train or trains moving toward the left is the same as the operation during the passage of a train or trains moving toward the right, and so no further explanation is required.

While a train is moving toward the right and is in the main section B—C it is possible that such train may run on to a sanded section of track rails, so that track relay T^B will close momentarily. In this event line relay L^B will close, auxiliary relay E^B will be open, and line relay L^C will close. Auxiliary relay E^C, however, cannot close because its pick-up circuit is open at contact 43 of track relay T^C. It follows that as soon as the train passes off of the sanded portion of track and track relay T^B opens, all four relays L^B, E^B, E^C and L^C will be open and both signals S^B and S^C will indicate stop.

While a train is moving toward the left in section B—C, if a sanded portion of track rails should be encountered, the result will be the same as before: that is, relay E^B cannot become energized because its pick-up circuit is open at contact 34 of track relay T^A, and so when the track relay T^B again opens, both of the end signals S^B and S^C will indicate stop, and both of the intermediate signals H^B and H^C will be extinguished.

If two cars moving in opposite directions should pass points A and D, respectively, at the same instant, track relays T^A and T^C will open simultaneously. Relays L^B and L^C so will then both be opened. Under this condition auxiliary relay E^C may become energized if there is a sufficient time interval between the closing of back contact 43 of track relay T^C and the opening of the front point 70 of contact 41 of line relay L^C. If relay E^C thus becomes closed, its stick circuit will be closed as soon as contact 41 opens and so relay E^B will remain closed. Relay E^B cannot close, however, because of its slow pick-up characteristic, and so signal S^B and signal H^B will both indicate stop. If relay E^C closes and remains closed, signal S^C will indicate caution and intermediate signal H^C will be energized, so that a train moving 75 from right to left may proceed through the stretch of track, whereas the train moving from left to right, upon finding signal H^B extinguished, must back up to siding X^A and wait there until it receives a proceed indication at signal S^B. It is, therefore, impossible for two cars moving in opposite directions and entering the stretch of track A—D at the same time to receive proceed indications at the intermediate signals H^B and H^C: only one car can receive such an indication at one of these signals, and the other car will be required to back out of the stretch of single track.

Referring now to Fig. 2, the circuits for the control of relays L^B, E^B, E^C and L^C are the same as the circuits for these relays in Fig. 1. The track circuits are likewise the same except that in preliminary section A—B the transformer and the relay are at 80 the left and right-hand ends of the section, respectively, instead of the right and left hand ends of the section, as in Fig. 1. Similarly, the transformer and relay for section C—D are reversed in position with respect to Fig. 1. In Fig. 2 signal S^B is located at point B and signal S^C is located at point C, the intermediate signals H of Fig. 1 being omitted.

Referring to signal S^B, the circuit for the proceed lamp G is from terminal F, through the back point of contact 57 of relay E^B, wire 75, front point of contact 50 of relay L^B, wire 76, lamp G, and wire 54 to terminal K. The circuit for the caution lamp 125

Y is from terminal F, through the front point of contact 57 of relay E^B, wire 77, lamp Y, and wire 54 to terminal K. The circuit for the stop lamp R is from terminal 5 F, through back point of contact 57, wire 75, back point of contact 50, wire 78, stop lamp R and wire 54 to terminal K.

The circuits for signal S^C are similar to those for signal S^B and will be understood 10 without further explanation.

As a car or train moving toward the right enters section A—B, the opening of track relay T^A will close the pick-up circuit for relay E^B, so that after the interval of time, 15 determined by the characteristics of this relay, the relay will close. When this occurs, the caution indication for signal S^B will be closed at contact 57, and this caution indication is maintained as long as the train 20 occupies any part of the stretch of track between points A and D. The opening of track relay T^A, of course, opens relay L^C, thereby closing at the back point of contact 65 the circuit for the stop lamp R of 25 signal S^C. This signal, therefore, continues to indicate stop as long as the train moving toward the right occupies any portion of the stretch. In all other respects the operation in Fig. 2 is the same as that of Fig. 1. 30 Although I have herein shown and described only two forms of apparatus embodying my invention, it is understood that various changes and modifications may be made therein within the scope of the 35 appended claims without departing from the spirit and scope of my invention.

Having thus described my invention, what I claim is:

1. In combination, a stretch of single 40 track used by traffic moving in both directions and divided into a main track section and a preliminary track section at each end of the main section, a track circuit including a track relay for each section, a line 45 relay adjacent each end of the stretch and having a pick up circuit controlled by all of said track relays, a stick circuit for each line relay controlled by the track relay for the main section and the track relay for the 50 preliminary section at the opposite end of the stretch but not by the track relay for the preliminary section at the end at which the line relay is located, an auxiliary relay adjacent each end of the stretch, a pick up 55 circuit for each auxiliary relay including a front contact of the adjacent line relay and a back contact of the track relay for the adjacent preliminary section, a stick circuit for each auxiliary relay including a back 60 contact of the adjacent line relay, and signals for the stretch controlled by said relays.

2. In combination, a stretch of single 65 track used by traffic moving in both directions and divided into a main track section and a preliminary track section at each end

of the main section, a track circuit including a track relay for each section, a line relay adjacent each end of the stretch and having a pick up circuit controlled by all of said track relays, a stick circuit for each line relay controlled by the track relay for the main section and the track relay for the preliminary section at the opposite end of the stretch but not by the track relay for the preliminary section at the end at which the line relay is located, an auxiliary relay adjacent each end of the stretch, one of said auxiliary relays having the characteristic of picking up slowly when energized and the other of said auxiliary relays having the characteristic of picking up quickly when energized, a pick-up circuit for each auxiliary relay including a front contact of the adjacent line relay and a back contact of the track relay for the adjacent preliminary section, a stick circuit for each auxiliary relay including a back contact of the adjacent line relay, and signals for the stretch controlled by said relays.

3. In combination, a stretch of single 90 track used by traffic moving in both directions and divided into a main track section and a preliminary track section at each end of the main section, a track circuit including a track relay for each section, a line relay adjacent each end of the stretch and having a pick up circuit controlled by all of said track relays, a stick circuit for each line relay controlled by the track relay for the main section and the track relay for the preliminary section at the opposite end of the stretch but not by the track relay for the preliminary section at the end at which the line relay is located, an auxiliary relay adjacent each end of the stretch, a pick up 95 circuit for each auxiliary relay including a front contact of the adjacent line relay and a back contact of the track relay for the adjacent preliminary section, a stick circuit for each auxiliary relay including a back contact of the adjacent line relay, a signal adjacent each end of said stretch; means for causing each signal to indicate proceed when the adjacent line relay and the track relay for the adjacent preliminary section are both 100 closed, caution when the adjacent auxiliary relay is closed, and either the adjacent line relay or the track relay for the adjacent preliminary section is open, and stop when the adjacent auxiliary relay is open and either the adjacent line relay or the track relay for the adjacent preliminary section is open; an auxiliary signal adjacent each end of said main section, and means for causing each auxiliary signal to indicate proceed or stop according as the adjacent auxiliary relay is 105 closed or open.

4. In combination, a stretch of single 110 track used by traffic moving in both directions and divided into a main track section

and a preliminary track section at each end of the main section, a track circuit including a track relay for each section, a line relay adjacent each end of the stretch and having a pick up circuit controlled by all of said track relays, a stick circuit for each line relay controlled by the track relay for the main section and the track relay for the preliminary section at the opposite end of the stretch but not by the track relay for the preliminary section at the end at which the line relay is located, an auxiliary relay adjacent each end of the stretch, a pick up circuit for each auxiliary relay including a front contact of the adjacent line relay and a back contact of the track relay for the adjacent preliminary section, a stick circuit for each auxiliary relay including a back contact of the adjacent line relay, a signal located adjacent each end of said main section; and means for causing each signal to indicate proceed when the adjacent line relay is closed and the adjacent auxiliary relay is open, caution when the adjacent auxiliary relay is closed, and stop when the adjacent line relay and auxiliary relay are both open.

5. In combination, a stretch of single track used by traffic moving in both directions and divided into a main track section

and a preliminary track section at each end of the main section, a track circuit including a track relay for each section, a line relay adjacent each end of the stretch and having a pick up circuit controlled by all of said track relays, a stick circuit for each line relay controlled by the track relay for the main section and the track relay for the preliminary section at the opposite end of the stretch but not by the track relay for the preliminary section at the end at which the line relay is located, an auxiliary relay adjacent each end of the stretch, a pick up circuit for each auxiliary relay including a front contact of the adjacent line relay and a back contact of the track relay for the adjacent preliminary section, a stick circuit for each auxiliary relay including a back contact of the adjacent line relay, two signals for governing traffic in opposite directions in said stretch, a proceed indication circuit for each signal controlled by a front contact of the associated line relay, a caution indication circuit for each signal controlled by a front contact of the associated auxiliary relay, and a stop indication circuit for each signal controlled by a back contact of the associated auxiliary relay.

In testimony whereof I affix my signature.
HENRY S. YOUNG.
